CLAIM

The ornamental design for an arcade game cabinet, as shown and described.

DESCRIPTION

FIG. 1 is a perspective view of a first embodiment of the arcade game cabinet;

FIG. 2 is a right side view;

FIG. 3 is a left side view;

FIG. 4 is a front view;

FIG. 5 is a back view;

FIG. 6 is a top view;

FIG. 7 is a bottom view;

FIG. 8 is a perspective view of a second embodiment of the arcade game cabinet;

FIG. 9 is a right side view;

FIG. 10 is a left side view;

FIG. 11 is a front view;

FIG. 12 is a back view;

FIG. 13 is a top view; and,

FIG. 14 is a bottom view.

The claimed design is shown with a symbolic break in its length. The appearance of any portion of the article between the break lines forms no part of the claimed design.

The broken line showing of portions of the arcade gaming cabinet forms no part of the claim.

1 Claim, 6 Drawing Sheets
